TRUNK HUNTING CIRCUIT

Orfeo Cesareo, Washington Township, Bergen County, N. J., assignor to Bell Telephone Laboratories, Incorporated, New York, N. Y., a corporation of New York

Application September 24, 1941, Serial No. 412,073

7 Claims. (Cl. 179—18)

This invention relates to telephone systems and has for its object to increase the speed of operation of automatic equipment.

More specifically the invention relates to a trunk hunting arrangement suitable for use in a call distributing office of the type disclosed and claimed in U. S. Patent No. 1,816,634 to W. W. Carpenter et al., July 28, 1931.

In that patent, idle operators' positions are identified by battery on the test conductor while 10 busy or vacant positions are unmarked, and a relay and stepping magnet function reciprocally until their circuits are opened by a test relay which operates when an idle position is found.

It being desired to increase the speed of hunting, in accordance with the present invention busy or vacant positions are marked with ground and a self-interrupting circuit is provided for the stepping magnet in series with a polarized test relay, and the test wiper of the switch, the circuit being so arranged that the magnet operates when the test wiper rests on a busy or vacant position and the test relay operates when the test wiper engages an idle position. The test relay when operated controls means for opening the test circuit and marking the position busy, and locks independent of both the stepping magnet and the position circuit.

The invention will be more clearly understood from a consideration of the following description in connection with the drawing which shows a trunk circuit embodying the invention.

When the trunk is seized, a bridge is closed across conductors 110 and 111, completing a circuit from battery through the upper winding of relay 116, contact 4 of relay 115, winding 2 of repeating coil 114, conductor 113, ring contacts of test jack 109, conductor 111, over the bridge at the calling office, conductor 110, tip contacts of test jack 109, conductor 112, winding 1 of repeating coil 114, contact 1 of relay 115, lower winding of relay 116 to ground. Relay 116 operates in this circuit and grounds conductor 141, operating relay 117. Ground on conductor 141 is extended over contact 1 of relay 140 to the sleeve of jack 109 and over contact 2 of relay 129 to lamp 119 and in parallel therewith over the auxiliary contact of jack 109 to conductor 142 leading to the service observing position.

Relay 117 closes a circuit from a source of machine ringing current through ballast lamp 118, contact 4 of relay 117, condenser 143, contact 6 of relay 129, through winding 4 of repeating coil 114, through the winding of relay 138 to battery and ground, as an indication to the calling sub-

scriber that the information operator is being called.

Relay 117 also connects ground over its contact 2, contact 5 of relay 129, contact 1 of relay 123, through resistance 144 to conductor 120 leading to the allotter. This circuit also extends over contacts 1 and 2 of relay 123, contact 3 of relay 140 to conductor 121 to mark this trunk as calling to the sequence storing circuit.

The allotter functions, in response to the grounding of conductor 120, in the manner described in the above-identified Carpenter et al. patent to start an idle sequence storing circuit hunting for the calling trunk. After a storing circuit has connected with the trunk by means of the ground on conductor 121, and has performed certain functions, a relay is operated which closes a locking circuit for itself between ground and conductor 122, thereby completing a circuit over contact 1 of relay 129, and contact 3 of relay 117 to the winding of relay 123 and battery.

Relay 123 operates, disconnecting ground from conductor 120, thereby disconnecting the trunk from the allotter. However, the connection between the trunk and the storing circuit is maintained by the locking circuit above traced.

Relay 123 also disconnects ground from conductor 121 and extends that conductor to the winding of relay 124 and battery.

As fully described in the above-mentioned patent, the storing circuits and associated trunks are seized one at a time by a start circuit which determines the order in which the trunks hunt for idle operators' positions. When the start circuit connects with the trunk it connects ground to conductor 121, operating relay 124.

Relay 124 starts the position finder 100 hunting for an idle operator's position. At contact 2 relay 124 closes a circuit from wipers 101 and 106 over contact 5 of relay 127, winding of polarized relay 125, back contact and winding of stepping magnet 107 to battery.

A portion of an operator's position is shown connected to the first terminals of wipers 101, 102 and 103. When the position is vacant, ground is connected to conductor 145 over the back contact of relay 131. When the position is occupied relay 131 is operated extending conductor 145 over the front contact of relay 131, normal contacts of hold key 132 and release key 133, back contact of relay 134 to battery through the winding of relay 146. With key 132, key 133 or relay 134 operated the position is marked un-

available by the connection of ground to conductor 145.

At contact 1, relay 124 connects ground through the winding of relay 126 to the operating circuit of magnet 107 between the winding of the magnet and the winding of relay 125.

If switch 100 is resting on an idle position circuit, battery connected to conductor 145 will complete a circuit for polarized relay 125 in series with relay 126. Relay 125, being polarized to respond to the current now flowing in this circuit, closes its left contact very rapidly, completing an obvious circuit for relay 127 which is also quick to operate. Relay 127 at contact 6 connects battery through resistance 128 to the winding of relay 125 to hold that relay operated. At contact 5, relay 127 disconnects the windings of relay 125 and magnet 107 from wiper 103 and at contact 4 connects ground to wiper 103 to mark the position busy.

If switch 100 is resting on a busy position circuit, ground on conductor 145 completes the above traced circuit of magnet 107 which interrupts its own circuit to advance switch 100 in search of an idle position circuit. The current flowing through relay 125 at this time is in the reverse direction so that the relay remains unoperated. During hunting ground on conductor 145 shunts relay 126 preventing its operation. When an idle circuit is found relay 125 functions as above described.

If conductor 145 is accidentally opened so that neither ground nor battery appears on the terminal engaged by wiper 103, the operation of relay 124 connects ground through the winding of relay 126 to the back contact and winding of magnet 107 and battery. Relay 126 is of high resistance and therefore magnet 107 cannot operate in series with it. Relay 126 is also slow to operate so that it cannot operate before relays 125 and 127 operate in connection with an idle position and is shunted as above mentioned when the position finder rests on a busy position. When the position finder encounters a position having an open test conductor, relay 126 operates, closing a circuit from ground over the right contact of relay 125, contact 1 of relay 127, contact of relay 126 to the winding of magnet 107 and battery. Magnet 107 operates, opening the circuit of relay 126 which releases, in turn releasing magnet 107 and advancing switch 100 to the next position circuit.

It is apparent that this circuit arrangement provides high speed hunting since the polarized testing relay permits the switch to advance as fast as the mechanism will operate. In addition means is provided to prevent delays caused by one or more position finders stopping on contacts connected to open position test conductors until released by the maintenance force.

For further operation of this trunk circuit and the position circuit, reference may be had to the above-mentioned Carpenter et al. patent.

While the invention has been described in connection with the particular call distributing system described in the Carpenter et al. patent, it is clearly applicable to any trunk hunting circuit employing self-operated switches, and has been so claimed.

A related trunk hunting arrangement is disclosed and claimed in the application of C. G. Spencer, Serial No. 412,059, filed September 24, 1941.

What is claimed is:

1. In a telephone system, a switch, a magnet

for causing said switch to advance in search of an idle trunk, a polarized relay, a test wiper for said switch, an operating circuit for said magnet including said polarized relay and said test wiper in series, means in busy trunks for operating said magnet over said circuit, means in idle trunks for operating said relay, and means under the control of said relay when operated by an idle trunk for stopping said switch and establishing a connection with said trunk.

2. In a telephone system, a switch, a magnet for causing said switch to advance in search of an idle trunk, a polarized relay, a test wiper for said switch, an operating circuit for said magnet including said polarized relay and said test wiper in series, means in busy trunks for operating said magnet over said circuit, means in idle trunks for operating said relay, and means under the control of said relay when operated by an idle trunk for disconnecting said relay and said magnet from said test wiper.

3. In a telephone system, a switch, a magnet for causing said switch to advance in search of an idle trunk, a polarized relay, a test wiper for said switch, an operating circuit for said magnet including said polarized relay and said test wiper in series, means in busy trunks for operating said magnet over said circuit, means in idle trunks for operating said relay, and means under the control of said relay when operated by an idle trunk for marking said trunk busy and for disconnecting said relay and said magnet from said test wiper.

4. In a telephone system, a switch, a magnet for causing said switch to advance in search of an idle trunk, a polarized relay, a test wiper for said switch, an operating circuit for said magnet including said polarized relay and said test wiper in series, means in busy trunks for operating said magnet over said circuit, means in idle trunks for operating said relay and means under the control of said relay when operated by an idle trunk for marking said trunk busy and for locking itself independent of said magnet and said test wiper.

5. In a telephone system, a switch, a magnet for causing said switch to advance in search of an idle trunk, a polarized relay, a test wiper for said switch, a first operating circuit for said magnet including said polarized relay and said test wiper, means in busy trunks for operating said magnet over said first circuit, means in idle trunks for operating said relay, means under the control of said relay when operated by an idle trunk for disconnecting said relay and said magnet from said test wiper, an auxiliary relay, a second circuit for said magnet, means to operate said auxiliary relay when said test wiper rests on a trunk which does not complete said first circuit, and means under the control of said auxiliary relay for completing said second circuit.

6. In a telephone system, a switch, a magnet for causing said switch to advance in search of an idle trunk, a polarized relay, a test wiper for said switch, a first operating circuit for said magnet including said polarized relay and said test wiper, means in busy trunks for operating said magnet over said first circuit, means in idle trunks for operating said relay, means under the control of said relay when operated by an idle trunk for disconnecting said relay and said magnet from said test wiper, an auxiliary relay, a second circuit for said magnet, means to operate said auxiliary relay when said test wiper rests on a trunk which does not complete said first

circuit, means under the control of said auxiliary relay to render said second circuit effective to operate said magnet, and means to operate said auxiliary relay and said magnet alternately until said test wiper reaches a trunk which completes said first circuit.

7. In a telephone system, a switch, a magnet for causing said switch to advance in search of an idle trunk, a polarized relay, a test wiper for said switch, a first operating circuit for said magnet including said polarized relay and said test wiper, means in busy trunks for operating said magnet over said first circuit, means in idle trunks for operating said relay, means under the control of said relay when operated by an idle

5 trunk for disconnecting said relay and said magnet from said test wiper, an auxiliary relay, a second circuit for said magnet, means to operate said auxiliary relay when said test wiper rests on a trunk which does not complete said first circuit, means under the control of said auxiliary relay to render said second circuit effective to operate said magnet, means to operate said auxiliary relay and said magnet alternately until said test wiper reaches a trunk which completes said first circuit, and means to release said auxiliary relay when said last-mentioned trunk completes said first circuit.
